UNITED STATES PATENT OFFICE

158,452

VELOCIPED

Donald W. Gill, Cincinnati, Ohio, assignor to The Frank F. Taylor Company, Norwood, Ohio, a corporation of Ohio

Application May 26, 1949, Serial No. 2,892

Term of patent 14 years

(Cl. D34—15)

To all whom it may concern:

Be it known that I, Donald W. Gill, a citizen of the United States of America, residing at Cincinnati, in the county of Hamilton and State of Ohio, have invented a new, original, and ornamental Design for a Velocipede, of which the following is a specification, reference being had to the accompanying drawing, forming a part thereof.

The figure is a perspective view of a velocipede, showing my new design.

I claim:

The ornamental design for a velocipede, as shown.

DONALD W. GILL.
